DOORCHECK

Alfred J. Schulz, Milwaukee, Wis., assignor to himself and Herbert H. Schulz, copartners, doing business as S-B Manufacturing Company, Milwaukee, Wis.

Application March 21, 1930, Serial No. 437,630
Renewed October 10, 1932

12 Claims. (Cl. 292—264)

This invention relates to improvements in door checks.

It is the primary object of the invention to provide a novel and improved door check structure in which a neat and simple means of enclosing and winding up the door check chain is provided, such means being under control of the operator to limit to any desired degree the length of chain exposed outside of the case.

10 In accordance with the objects of this invention it is my desire to make the case for the chain, and the reel upon which the chain is wound, as small as possible, and to this end I propose to place the reel eccentrically within the 15 case and to provide numerous features of design including a special form of link in the chain to facilitate its close winding upon the reel.

15 A further object of the invention having to do with neatness of appearance is the provision of 20 a special form of keeper in which the disk at the end of the chain is received in such a way as to avoid removal of the finish upon the keeper.

25 Another object of the invention has reference to the simplification of detent means for fixing 30 the position of the reel whereby to relieve the chain of spring tension, and also to lock the chain when desired.

In the drawing:

Figure 1 is a view showing an illustration of 35 a door check embodying this invention.

Figure 2 is a view of the unit thereof containing the reel, the case being broken away in transverse section to expose the reel and the chain wound thereon.

35 Figure 3 is a view taken in section in the plane indicated at 3—3 in Fig. 2.

Figure 4 is a detail view showing in perspective and in mutually spaced relation, the component parts of the reel and detent therefor.

40 Figure 5 is a detail view taken in section in the plane indicated at 5—5 in Fig. 1.

Like parts are identified by the same reference characters throughout the several views.

45 The device comprises a keeper unit 6 and an anchorage unit 7. While it is particularly unimportant in the present invention which unit is mounted upon the door and which upon the casing, I have shown the keeper 6 mounted upon the door 8, and the anchorage member 7 mounted on the door casing 9.

50 The anchorage member comprises a case 10 formed of sheet metal and shouldered at 11 to provide a rectangular base 12 having holes 55 through which the screws 13 may be inserted

to mount the member on a door frame or casing.

5 Fitted within the base 12 is a plate 15 provided, as shown in Fig. 2, with screw holes registering with the openings in the base. This plate confines a detent slide 16 having thumb pieces 17 at its ends and detent teeth formed upwardly in its face as shown at 18 in Figs. 3 and 4. This slide is slotted at 19 to receive the rivet 20 which passes through the shell 10 and 10 plate 15 to hold the parts together and also serves as an axis upon which the reel 21 rotates. It is particularly to be noted that the rivet 20 is eccentric with reference to the axis of the shell 10, being located at one side of a diameter of such shell passing through the opening 22 from which the chain 25 issues. This eccentricity permits the winding of an extra half turn of chain upon the drum or reel 21 within a space which would otherwise be inadequate. 20

25 The drum or reel 21 houses a torsion spring 26 which is anchored to the drum and to the plate 15, as shown in Fig. 3. The rearward margin of the drum or reel is flanged outwardly and provided with axially projecting teeth in the 25 manner of a crown wheel ratchet, the reel being free to rotate when the slide 16 is in the position shown in Fig. 3, but adapted for engagement by the teeth 18 of the slide when the slide is in the position in which it appears in Fig. 2. 30

35 A strap 27 holds the innermost end of the chain to the drum or reel 21. The first link of the chain is disposed flat upon the periphery of the drum and is preferably curved in substantial conformity therewith, as shown at 28 in Fig. 2. The end of the chain carries the usual button 30 which, in the retracted position of the parts, will normally close the flared opening 22 through which the chain issues from its case. When the detent slide 16 is manipulated upwardly, as shown in Fig. 3, to permit the drum to rotate, the chain may be withdrawn against the torsion of spring 26 and the button may be inserted into the opening 31 in the keeper unit. 40

45 The keeper unit is formed integrally of sheet metal having a continuous peripheral flange at 32 (Fig. 5), a downwardly formed apron 33 leading to the opening 31, and a slot 34 communicating with such opening to receive the shank 35 of the button 30. 50

55 A novel feature of the keeper unit consists in the provision of upturned flanges 36 at each side of the slot 34. Upon these flanges rides the annular flange 37 on the special button employed in the device. In practice the outwardly

presented edges of the marginal flanges 36 will wear bright due to friction of the button flange 37 thereon, but the two bright lines thus formed at the margin of slot 34 will not detract from the appearance of the device. This arrangement avoids all other wear between the parts and hence preserves the finish on the face of the keeper unit 6.

The torsion spring 26 is sufficiently strong to draw the chain 25 into the shell 10 whenever the button 30 is released. The spring will also tend to keep the door 8 closed unless the reel is relieved of spring torsion by manipulation of the detent slide 16. Ordinarily, therefore, the detent slide will be actuated to engage the teeth of the reel whenever the chain is extended to the desired degree. If desired, the detent slide may be locked with the parts in the position shown at Fig. 1, in which case the device will function as a safety latch for the door to hold it completely closed.

When the chain is not in use a pressure upwardly on slide 16 will release the reel, and the chain will be fully retracted into the casing 11 into which it fits with almost no loss of space by virtue of the eccentricity of the rivet 20 whereby a relatively great length of chain is housed in a relatively small case. When the chain is fully retracted the shank portion of the rivet will be received into the flared opening 22 in the case, and such opening will be closed by the button at the end of the chain.

I claim:

1. In a door check, the combination of a case member, a slotted base, a plate in said base, a shaft connecting said case and plate, a detent projecting from said base and slidable with respect to said shaft, said detent being provided with a tooth within said case, a reel mounted on said shaft and provided with peripheral teeth with which the tooth of said detent may be engaged upon manipulation of the detent, and a chain connected with said reel and adapted to be wound thereon, said reel being provided with a torsion spring acting upon it in a direction tending to wind said chain upon the reel.

2. A device of the character described comprising a shell formed to provide a slotted base, a detent slide reciprocable transversely in the slots of the base and having a detent portion within said shell, a plate enclosing said slide within said base, a pivot member connecting said plate and shell, a reel mounted upon said pivot member and provided with teeth engageable by the detent portion of said base, a torsion spring housed within said reel, and a chain having its end fastened to said reel.

3. A device of the character described comprising a shell formed to provide a slotted base, a detent slide reciprocable transversely in the slots of the base and having a detent portion within said shell, a plate enclosing said slide within said base, a pivot member connecting said plate and shell, a reel mounted upon said pivot member and provided with teeth engageable by the detent portion of said base, a torsion spring housed within said reel, and a chain having its end fastened to said reel, the first link of said chain being curved in conformity with the periphery of said reel.

4. A device of the character described comprising a shell formed to provide a slotted base, a detent slide reciprocable transversely in the slots of the base and having a detent portion within said shell, a plate enclosing said slide

within said base, a pivot member connecting said plate and shell, a reel mounted upon said pivot member and provided with teeth engageable by the detent portion of said base, a torsion spring housed within said reel, and a chain having its end fastened to said reel, said pivot member being eccentrically located with reference to said shell, said shell being provided with an opening for said chain, and said pivot member being disposed at one side of a diameter 10 intersecting said opening.

5. In a door check, the combination with a chain and retracting reel to which the chain is operatively connected, of means for operating said reel in a chain retracting direction, and a 15 housing in which said reel is mounted, said reel being eccentrically mounted with respect to the center of the housing and adapted to receive successive portions of said chain upon chain portions previously wound on said reel at a 20 gradually increasing radial distance from the axis of the reel, and said housing having an aperture for said chain affording access to the portion of the housing which is eccentrically remote from the axis of said reel, whereby the 25 more remote portion of the housing receives the portion of the chain most remote from the axis of the reel, and the chain, as wound upon the reel, substantially fills said housing.

6. In a door check, the combination with a 30 casing provided with an aperture, of a reel provided with means at its axis supporting it for rotation eccentrically with reference to said casing in a position to leave the larger side of said casing accessible to said aperture, a chain operable through the aperture and connected with the reel to be wound thereon, and a spring acting on said reel in a chain winding direction, the eccentricity of said housing being sufficient to receive the portions of said chain last to enter 40 said housing and wound upon chain portions previously wound about said reel.

7. In a door check device, the combination with a casing provided with an aperture, a flexible connector passing through said aperture, 45 anchorage means including manually separable portions one of which is carried by the free end of said connector, a reel within the casing to which the flexible connector is attached, said reel including a radial flange, and spring means 50 acting on said reel in a direction to wind said connector thereon, of a manually operable detent disposed between said flange and the casing and adapted positively to lock said reel against rotation in either direction, said detent and reel 55 having mutually engageable interlocking portions.

8. In a door check, the combination with an apertured casing and a flexible connector, of a radially flanged reel rotatably mounted within 60 said casing to which said connector is attached, teeth carried by said reel flange, and a manually operable detent fixed against movement with said reel and movable to and from the path of said teeth, said detent having complementary teeth 65 engageable with the teeth of said reel flange to effect a positive locking of said reel against movement in either direction.

9. In a door check, the combination with an apertured casing, a flexible connector movable 70 through the aperture of the casing, a reel within the casing to which the connector is attached to be wound thereon, a detent device permanently mounted within the casing and manually adjustable therein, and means carried by said 75

detent device and reel engageable at diametrically opposite points on said reel upon the manipulation of said detent device for locking said reel against rotation in either direction.

- 5 10. In a door check, the combination with a casing provided with an aperture and a flexible connector passing through the aperture, of a rotor mounted within said casing and comprising integrally a hub to which said connector is attached, a marginal radial flange, and crown teeth at the periphery of said flange, a detent 10 slidable transversely of said casing and provided integrally with teeth complementary to the crown teeth spaced for a distance approximately 15 equal to the diameter of the flange of said rotor and engageable therewith at opposite sides of the rotor to resist rotation of said rotor.
11. In a door check, the combination with a casing having a base, an annular wall and a top, 20 of a flexible connector, a reel within said casing to which said connector is attached, a detent slidable transversely of said casing and provided with means engageable with and disengageable

from said reel, said casing being apertured for said connector and detent, a back plate supporting said detent in operative relation to said reel, and pivot means for said reel extending through said casing and back plate and headed to maintain the parts in assembly. 5

12. In a door check, the combination with a casing having a base, an annular wall and a top, of a flexible connector, a reel within said casing to which said connector is attached, a detent 10 slidable transversely of said casing and provided with means engageable with and disengageable from said reel, said casing being apertured for said connector and detent, a back plate supporting said detent in operative relation to said reel, 15 and pivot means for said reel extending through said casing and back plate and headed to maintain the parts in assembly, said detent comprising a plate slotted to receive said pivot means while permitting of the required movement of 20 said detent.

ALFRED J. SCHULZ.
